UNITED STATES PATENT OFFICE

2,005,775

HEEL ATTACHING PLATE

Frank B. Dopp, St. Louis, Mo., assignor to Perma Corporation, a corporation of Illinois

Application September 21, 1933, Serial No. 690,306

9 Claims. (Cl. 36—34)

This invention relates to a shoe heel attaching plate and more particularly to certain features in the construction thereof to more accurately form the heel attaching plate construction defined in the application of August G. Eichhorn for improvements in Shoe construction, filed April 8th, 1932, Serial Number 603,995.

An object of the invention is to locate the front edges of the front opposed fastening prongs of the heel so that they will lie in a plane with the front face of the front apertured ear on the attaching plate so that the apertured ear will serve as a truss for the front edge of the plate between the two front prongs of the plate.

Another object of the invention is to locate the next pair of fastening prongs on the heel attaching plate arranged to the rear of the front prongs in alignment with a second apertured ear stamped from the plate body so that the ear will serve as a truss for the middle section of the plate between the two second sets of prongs from the front of the plate.

A further object of the invention is to provide the heel attaching plate with a punched out opening midway the ends of the apertured ears with half of each opening extending into the ears so that in bending the ears with suitable dies to assume right angular positions to the plate, the fold edge of the ears will not become distorted by crowding of the metal in shaping the plate proper into concaved-convexed formation both transversely and longitudinally, thus assuring the pin apertures in the ears to assume positions in perfect alignment relative to the surface of the plate that is to contact the heel seat surface of a shoe sole.

A further object of the invention resides in flattening the peripheral edge portion of the heel attaching plate.

A further object of the invention resides in providing the fastening prongs with inner beveled or swedged surfaces extending approximately half way down the prongs so that the penetrating ends of the prongs will be forced outwardly when forced under instant plunger pressure into contact with a last plate after passing through the heel seat material of a shoe in securing the plate to the heel seat thereof.

A further object of the invention is to provide both the inner and outer faces of the fastening prongs with beveled faces to cause the prongs to pass straight through the heel seat material before the penetrating ends of the prongs are clinched over the insole of a shoe.

A further object of the invention is to bevel

or swedge only the outer faces of the fastening prongs of the heel attaching plate so that the penetrating ends of the prongs will bend inwardly and clinch upon the insole after passing through the heel seat material of a shoe.

A still further object of the invention is to form all of the fastening prongs on the peripheral edge of the heel attaching plate.

The objects and advantages of the invention will be readily apparent from the foregoing description taken in connection with the accompanying drawing, wherein:

Fig. 1 is a top plan view of a heel attaching plate embodying the features of my invention.

Fig. 2 is a side elevation of the heel attaching plate.

Fig. 3 is a front elevation of the heel attaching plate.

Fig. 4 is a sectional view taken on line 4—4 of Fig. 1.

Fig. 5 is a plan view of the heel attaching plate as it appears after being blanked out.

Fig. 6 is a view showing the heel attaching plate secured to the heel seat of a shoe.

Fig. 7 is a view showing a heel positioned on the plate and heel seat prior to a lock pin being inserted into the heel.

Fig. 8 is a sectional view of the finally attached heel and the shoe.

Fig. 9 shows a modified form of fastening prong on the plate.

Fig. 10 shows a further modified form of fastening prong on the plate.

Fig. 11 shows another modification of prong.

Fig. 12 shows a further modification of prong.

Fig. 13 shows the plate without the flat marginal portion.

The heel attaching plate with which my invention concerns, embodies a metal body portion 1 corresponding in shape to the base or base seat of a shoe heel which is dished or concaved-concaved both longitudinally and transversely and is provided with a front pair of fastening prongs 2, a rear pair of fastening prongs 3' and an intermediate pair of fastening prongs 4 directed upwardly from the peripheral edge of the body 1, and, further provided with a pair of spaced downwardly directed ears 5 and 6 having the lock pin receiving openings or apertures 7 and 8, respectively, and having their edges suitably curved as at 5' and 6'.

In carrying out the aim of my invention, I propose to form the ear 5 at the extreme front edge of the plate 1 so that the front face 9 of the ear 5 will lie in a plane with front edges 55

10 of the front prongs 2 at their juncture or fold edge 11 with the plate 1 so that the ear 5 will thereby serve as a truss member for the front edge of the plate directly between the front 5 fastening prongs 2. The fold edge *a* of the ear 5 is provided with a suitable relief opening 12 midway its ends thereof, which opening serves to prevent distortion of the ear 5 when folding the ear downwardly relative to the plate 1, by 10 breaking the otherwise continuous fold line *a* to relieve crowding of the metal against the lock pin receiving opening 7 and thereby permit the fold edge to assume the same arc as the inner face of the plate 1.

15 I further locate the fold edge 13 of the plate ear 6 on a line midway the width of the intermediate fastening prongs 4 so that the center line of the ear 6 between the front and rear faces thereof will be in a straight line with the midway points of the prongs 4, thus causing the ear 20 6 to serve as a truss member on the plate directly between the opposed fastening prongs 4.

25 I provide the fold edge 13 of ear 6 with a suitable relief opening 14 midway the ends thereof, which opening serves to prevent distortion of the ear 6 when bending the ear downwardly relative to the plate 1, by breaking the otherwise continuous fold line 13 to relieve crowding of the metal adjacent the lock pin receiving opening 8, and thereby permit the fold edge 13 to 30 assume the same arc as the inner face of the plate 1.

35 This arrangement of the ears 5 and 6 relative to the fastening prongs 2 and 4 serves to provide a heel fastening plate which will be properly reinforced or stiffened directly between the aforesaid fastening prongs.

40 By providing the ears 5 and 6 of the plate 1 with the relief openings 12 and 14 so as to extend beyond both sides of the fold edge thereof, the 45 openings 7 and 8 in the ears 5 and 6 will not be disturbed as to register thereof after the ears have been bent or folded into proper position relative to the plate body 1. This is important so that after the heel has been forced to the heel seat A of a shoe sole under pressure of a plunger B, there will be no difficulty in forcing a lock pin 15 through the ear openings 7 and 8 after 50 having been inserted into an opening 16 in a heel C, after the heel having slotted recesses 17 and 18 to receive the apertured ears of the plate 55 has been positioned on the heel seat of the shoe sole and held in proper position by suitable pressure to cause the heel opening 16 to register with the ear openings 7 and 8.

60 Due to the pressure exerted on the heel for holding it properly on the heel seat of the shoe, it is apparent that after the pressure has been released, the resiliency of the plate and the natural tendency of the heel to move outwardly due to the peripheral edge thereof having been forced 65 into the flexible material of the heel seat, the pin will bind in the ear opening, thereby securely holding and locking the heel against displacement on the heel seat of the shoe sole.

70 To insure the most perfect fit of the marginal edge of the plate 1 with the peripheral edge D of the heel seat A of a shoe E, I propose to flatten the marginal edge portion 1' of plate 1, as shown.

75 The fastening prongs 2, 3 and 4 are each, in one form, provided with outer beveled faces 19 and inner beveled faces 20 which extend from the points of the prongs approximately half way up the prongs. This double beveling of the

prong faces serves to cause the prongs to be forced straight through the heel seat material of the shoe and to clinch at will when the points of the prongs are brought into contact with a plate 21 on a last 22 upon which the shoe to be provided with the heel fastening plate is lasted.

5 In a modified form of fastening prongs one of which is shown in Fig. 9, the same is beveled as at 19' on the outer face only, thus causing the points of the prongs to bend inwardly and against 10 the insole of the heel seat material when brought into instant contact with the anvil plate 21 of the last 22.

15 In a further modified form of the fastening prongs, one only of which is shown in Fig. 10, the same is beveled as at 20' on the inner face only, thus causing the points of the prongs to bend outwardly and against the insole of the heel seat material when brought into contact with the anvil surface 21 of a last 22.

20 In the modification shown in Fig. 11 the fastening prong 2, only one of which is shown, has its outer face provided with a longer beveled surface 19'' and its inner face provided with a relatively short beveled surface 20'' so as to cause the prongs to drive straight but clinch toward the inside.

25 In the modification shown in Fig. 12, the fastening prong 2, only one of which is shown, has its outer face provided with a short beveled surface 19''' and its inner face provided with a relatively long beveled surface 20''' so as to cause the prong to drive straight but clinch toward the outside.

30 The plate modification shown in Fig. 13 is the same as the plate shown in Fig. 3, with the exception that the peripheral edge portion thereof is not flattened, as in Fig. 3, at 1'.

35 Due to the fact that the outer surface of the plate body 1 is convexed longitudinally and transversely with a flat marginal edge and there is uniform pressure exerted upon the entire plate area by the driving member B as the lasted shoe is supported by a work support F, the driving pressure has a tendency to force the fastening prongs straight into and through the heel seat material of the shoe before the points of the prongs are clinched to the insole of the heel seat material.

40 From the foregoing description, it is apparent 45 that I truss the plate directly between two opposed pairs of fastening prongs, that I relieve the fold edge of one of the apertured ears from the crowding of metal adjacent the pin aperture therein when bending the ear into position so as to prevent misalignment of the pin openings in the plate ears, and that I so bevel the fastening prongs as to cause the fastening prongs to be forced straight through the heel seat material of a shoe and to cause clinching of the prongs against the insole in 50 the direction desired.

55 The many advantages of the herein described invention will readily suggest themselves to those skilled in the art to which the heel attaching plate relates.

60 What I claim is:

65 1. In combination with a shoe heel attaching plate structure having a pair of apertured lock pin engaging ears, adapted to be permanently secured to the heel seat of a shoe sole by opposed pairs of fastening prongs, of bevel faces on the prongs, the front pair of prongs having their front edges at the juncture thereof with the plate disposed in a plane with the front face of one of the apertured lock pin engaging ears.

2. In combination with a heel attaching plate adapted to be permanently secured to the heel seat of a shoe sole by fastening prongs, of beveled faces on the prongs, an apertured ear disposed directly between two prongs at the front corners of the plate with the front edges of said prongs at the juncture thereof with the plate being in a plane with the front face of the apertured ear so that the apertured ear will serve as a truss member for the front edge of the plate. 10
3. In combination with a heel attaching plate adapted to be permanently secured to the heel seat of a shoe sole by fastening prongs, of beveled faces on the prongs, an apertured ear disposed directly between two prongs at the front corners of the plate with the front edges of said prongs at the juncture thereof with the plate being in a plane with the front face of the apertured ear so that the apertured ear will serve as a truss member 15
- 20 for the front edge of the plate, a second apertured ear disposed directly between the pair of opposed prongs to the rear of the front pair of prongs and serving as a truss member for the plate between said pair of prongs to the rear of the front pair of prongs.
4. In combination with a heel attaching plate adapted to be permanently secured to the heel seat of a shoe sole by fastening prongs, of beveled faces on the prongs, an apertured ear disposed directly between two prongs at the front corners of the plate with the front edges of said prongs at the juncture thereof with the plate being in a plane with the front face of the apertured ear so that the apertured ear will serve as a truss member 25
- 30 for the front edge of the plate, a second apertured ear disposed directly between the pair of opposed prongs to the rear of the front pair of prongs and serving as a truss member for the plate between said pair of prongs to the rear of the front pair of prongs and the fold edge of the front apertured ear having a relief opening midway its ends to prevent distortion of the ear when bending into 35
- 40 position to prevent misalignment of the aperture of the front ears with the aperture of the ear disposed to the rear of the front ear.
5. In combination with a heel attaching plate having fastening prongs and apertured lock pin engaging ears, of beveled inner and outer faces on the prongs and the fold edge of one of the ears having an opening midway its ends to relieve the crowding of metal in bending the ear into final position at a right angle to the plate. 5
6. In combination with a heel attaching plate having fastening prongs and apertured lock pin engaging ears, of beveled inner faces on the prongs and the fold edge of one of the ears having an opening midway its ends to relieve the crowding of metal in bending the ear into final position at 15
- 20 a right angle to the plate.
7. In combination with a heel attaching plate having fastening prongs and apertured lock pin engaging ears, of beveled outer faces on the prongs and the folded edge of one of the ears having an opening midway its ends to relieve the crowding of metal in bending the ear into final position at 25
- 30 a right angle to the plate.
8. A heel attaching plate including a dished heel seat plate, a front, rear and intermediate pair of opposed fastening prongs, beveled faces on the prongs, a front and a rear apertured lock pin engaging ear, the front ear being disposed directly between the front pair of prongs and with the front face of said ear lying in a plane with the front fold edge of the front prongs, the fold edge of the front ear having an opening midway its ends and the rear apertured ear being disposed directly between the intermediate pair of opposed 35
- 35 fastening prongs. 35
9. A heel attaching plate having a dished body portion, apertured ears struck up from the material of said body portion and said dished body portion having its peripheral edge portion flattened relative thereto to provide unbroken upper and lower marginal plane surfaces therefor. 40

FRANK B. DOPP.
